DESIGN FOR A SWINGING TEAPOT OR ARTICLE OF SIMILAR NATURE

Warren I. Tycer, Zanesville, Ohio

Application June 15, 1942, Serial No. 107,203

Term of patent 14 years

To all whom it may concern:

Be it known that I, Warren I. Tycer, a citizen of the United States of America, and a resident of Zanesville, in the county of Muskingum and State of Ohio, have invented a new, original, and ornamental Design for a Swinging Teapot or Article of Similar Nature, of which the following is the specification, reference being had to the accompanying drawing, forming a part thereof.

Figure 1 is a side elevational view of a swinging teapot or article of similar nature, showing my design; and

I claim:

The ornamental design for a swinging teapot or article of similar nature, substantially as shown.

WARREN I. TYCER.
